WARP BEAM

Frederick C. Washburn, New Bedford, Mass.

Application September 1, 1931. Serial No. 560,536

4 Claims. (Cl. 242—118)

This invention relates to warp beams more particularly to improvements in beam heads for warp beams of the type shown and described in my United States Patent No. 1,741,800, dated December 31, 1929. The principal object of the invention is to provide improved means for tensioning the heads against the beam ends so that the heads will not separate from the beam or become deformed by the pressure of the yarn wound upon the beam.

In the manufacture of warp beams the cast iron discs formerly employed as beam heads have largely been superseded by lighter and less rigid heads formed of pressed steel or laminated wood. Although the lighter heads are not subject to breaking or cracking from casting defects and are generally more satisfactory than the cast iron discs, they are liable to spreading at their peripheries or to become separated from the beam ends owing to the axial pressure applied against their inner faces by the mass of yarn upon the roll. It has accordingly been found desirable to reinforce the lighter and more flexible heads, and several expedients have been devised in an effort to stiffen and prevent angular deformation of the heads.

These expedients have usually consisted in providing local reinforcement at the center of the heads by forming radial ribs in the pressed steel heads, by providing reinforcing discs around the shaft opening, or by utilizing both arrangements in combination. Although these reinforcing devices have assisted in strengthening the central portion of the heads and have to some extent obviated actual separation thereof from the beam ends, they have not satisfactorily overcome the spreading tendency at the periphery of the beam head. It is consequently found that the lighter heads become permanently dished outwardly after repeated use, as a result of the accumulating pressure exerted against the peripheral margin of the heads as the beam fills.

It is therefore the principal purpose of the present invention to avoid the objectionable dishing or curling at the peripheries of light-weight beam heads by forming an annular shoulder or abutment on the outer face of the beam head and providing a rigid, non-compressible bracing member arranged to bear at its periphery against said shoulder to resist outward deflection at the rim of the head. An initial inward deformation or cupping may be induced in the heads before they are secured to the warp beam, to allow a very slight spreading at

the rims of the heads without causing an outwardly dished set at their peripheries. To the attainment of these objects, the head is preferably made slightly concavo-convex and provided with a concentric annular shoulder bordering a shallow recess of substantial width in its convex surface, a bracing plate preferably is inserted in the recess with its periphery abutting said shoulder and with its central portion spaced from the central portion of said recess, and the plate is clamped to the head under sufficient pressure to draw together said spaced central portions. The head is accordingly tensioned against distorting strains directed against the periphery of its inner concaved side.

A further object of the invention is to provide a clutch collar on the inner concave face of the heads, said collar having spaced inwardly directed jaws arranged to receive an interior cross support of the beam to restrain relative rotation between the beam cylinder and its heads.

Recommended embodiments of the invention are illustrated in the accompanying drawing, in which:

Fig. 1 is a broken longitudinal section of the improved warp beam, illustrating one form of head-tensioning means;

Fig. 2 is an enlarged end view of the same with the periphery of the beam head broken away;

Fig. 3 includes front and edge views of the clutch collar;

Fig. 4 is an enlarged section showing the arrangement of the bracing plate of Fig. 1, prior to the clamping of the plate to the head; and

Figs. 5 to 8 are views similar to Fig. 4 illustrating optional arrangements of the bracing plate.

The body of the warp beam may comprise a cylinder or barrel 11, preferably of built-up construction and consisting of interlocking staves, and interior supports preferably including a series of crossed supporting members 12 and 13 upon which some of the barrel staves are mounted as by bolts 14. The supporting members, which may be formed of stout wooden blocks, are rigidly secured face to face and at right angles to each other by nails 15 or other suitable fastening means, and the blocks have axial openings receiving the beam shaft 16. One pair of the crossed supports is arranged near each end of the cylinder 11 in order that one of the members may form part of a clutch subsequently to be described.

The beam heads 17 may be formed of wood,

either single ply or laminated, of pressed steel, or of other light-weight material which is sufficiently rigid and durable in use, and they are preferably preformed as concavo-convex discs, 5 as aforesaid. The concavity of the heads is considerably exaggerated in Fig. 1; it need only be slight in any case, to overcome the outward spreading tendency at the periphery of the head, and in some cases may be dispensed with altogether. The heads are mounted upon the projecting ends of the shaft 16 and may have 10 annular grooves 18 receiving the ends of the cylinder 11, and a grooved belt race 19 around their peripheral edges. Nuts 20 threaded upon 15 the shaft serve to secure the heads against the beam ends.

In the structure shown in Figs. 1 and 4, the outer, convex side of the head has a concentric recess 21 providing an outer annular shoulder 20 or abutment 22, and the recess is formed with an annular step 23 adjacent the shoulder 22 so that the recess is deeper in its central region than at its periphery. The beam head preferably has substantial thickness, and the shoulder 25 is located a considerable distance from the axis of the head. A flat, metal, bracing plate or disc 24 fits within the shoulder 22 and seats at its periphery upon the step 23, leaving a space 25 between its inner face and the bottom 30 of the recess 21 at said central region (Fig. 4). The plate is clamped to the head by bolts 26, preferably after applying pressure upon the outer side of the plate and the inner side of the head respectively, to close the space 25 at the 35 central portion of the tensioned members, as indicated at 27 (Fig. 1). When so secured, the peripheral edge of the non-compressible bracing plate 24 bears against the shoulder 22 thereby exerting a radial stress directed against said 40 shoulder which, owing to its distance from the center of the head and the thickness of the head, serves as a fulcrum analogous to that of a bellcrank, so that an axial force directed against the peripheral margin of the head at its 45 opposite side (as by the yarn wound on the beam) and tending to bind or deflect the rim of the head outwardly, is effectively resisted.

The resisting stress of the bracing plate is enhanced when, as shown, an initial inward concavity of the head is induced and maintained by clamping the plate to the head under pressure thereby to close the opening 25 between the plate and the head. Said space may be provided in various ways, some of which are illustrated in Figs. 5 to 8. In Fig. 5, a washer 28 takes the place of the step 23 of Figs. 1 and 4; in Fig. 6 the bracing plate is dished or sprung outwardly at 29 to provide the initial central space between the plate and bottom of the head 55 recess; in Fig. 7 the plate has radial ribs 34 and an inwardly offset rim 30 at its periphery; and in Fig. 8 the plate has an annular rib 31 providing a projection on its inner surface adjacent its periphery. The initial central space 60 25 may be varied in depth according to the degree of tension desired.

The inner heads of the bolts 26 may seat against a plate or collar 32 on the inner face of the head, and in the preferred form illustrated 70 in Figs. 1 to 3, the collar has parallel inwardly directed jaws or flanges 33 receiving and mating with one of the cross blocks of the end supports. The clutch jaws accordingly cooperate with the cylinder supports to prevent relative rotation between 75 the cylinder and its heads, even when the

beam and its yarn load are rotating at a high speed with one or both of the heads under braking restraint. This feature is an aspect of the present invention which may be employed independently of the head tensioning devices above 80 described, and constitutes an improvement upon the clutch elements described and claimed in Patent No. 1,741,800.

A warp beam constructed as above described is simple and relatively inexpensive to manufacture and has been found to be durable and satisfactory in use. The improved structure of the beam heads and bracing plates obviates spreading or outward cupping of the lightweight heads, and is especially applicable to heads of laminated wood which are relatively inexpensive. It will be understood, however, that structural details of the device herein shown and described may be varied for particular purposes without departing from the essence of this invention as defined in the following claims.

I claim:

1. A warp beam comprising a cylinder, beam heads secured against the opposite ends of the cylinder, each head having a substantially circular, concentric recess in its outer surface providing an annular abutment distant from the axis of the head, and a rigid bracing disc fitting within the recess of each head with its periphery bearing against said shoulder, and means for clamping the central portions of the discs against the outer surfaces of the respective heads, so that the radial stress of the rigid discs resists outward angular deflection of the rims of the heads.

2. A warp beam comprising a cylinder, beam heads secured against the opposite ends of the cylinder, each head having a substantially circular, concentric recess in its outer surface providing an annular abutment distant from the axis of the head, and a rigid bracing disc fitting within the recess of each head with its periphery bearing against said shoulder, and means for clamping the discs against the respective heads, so that the radial stress of the rigid discs resists outward angular deflection of the rims of the heads, the central portion of each beam head being tensioned against its bracing disc by said clamping means, to induce an inward curvature of the head.

3. A warp beam comprising a cylinder, beam heads secured against opposite ends of the cylinder, each head having a substantially circular, concentric recess in its outer face providing an annular shoulder bordering said recess, and a rigid bracing disc fitting within the recess of each head and bearing against said shoulder and against the head at an annulus adjacent said shoulder, the central portion of the disc being initially spaced from the bottom of the recess elements bearing against the central portions of the respective discs and tending to clamp the discs to the heads and to close said spaces thereby to induce an inward curvature of the heads, the central portions of the heads being thus drawn into engagement with said disc portions and the outward radial stress of the tensioned discs resisting outward angular deflection of the rims of the heads.

4. A warp beam comprising a cylinder, beam heads secured against the opposite ends of the cylinder, the heads being inwardly concaved and each head having a substantially circular, concentric recess in its outer surface providing an annular shoulder bordering said recess, a rigid

bracing disc fitting within the recess of each head and bearing flatwise against the outer portion of said recess at an annular band adjacent said shoulder, the central portion of the disc being initially spaced from the bottom of the recess, and clamping bolts passing through said central portion of the discs and through the heads, said bolts being tensioned to draw the head and plate together at the central portions thereof and substantially close said space, thereby tending to maintain the inward concavity of the heads. 80
